SLIDE HOLDER FOR CALENDARS OR THE
LIKE

Max Vogel, Bridgeport, Conn.

Application December 8, 1941, Serial No. 422,182

4 Claims. (Cl. 40—65)

The present invention relates to an improved slide holder for calendar or the like, and has for an object to provide a device of this character which may be economically manufactured from sheet material, as for instance cardboard, and in which stop means is provided as an integral part of the members of which the device is constructed for the purpose of limiting the movement of the slide member of the device relative to the enclosing or envelope member.

A further object is to provide such means which will not add appreciably to the thickness of the holder so that the invention may be effectually incorporated in a relatively flat type holder to be carried in the vest pocket.

Another object is to provide stop tab means having an integral connection to one of the members of the slide holder extending in parallel relation to the direction of sliding movement of the slide member so that a maximum resistance to tearing or bending is provided, and further to provide such stop means which will permit of a relatively long projection of the slide member from the holder in both directions so that this relatively long movement may be utilized in connection with relatively long calendar data, or other types of data printed upon the members of the device.

A further object is to provide stop means which will not impair the use of the full front surfaces of the holder and slide members to contain printed data.

With the above and other objects in view embodiments of the invention are shown in the accompanying drawing, and these embodiments will be hereinafter more fully described with reference thereto, and the invention will be finally pointed out in the claims.

In the drawing:

Fig. 1 is a front elevation of a slide holder for a calendar, partially broken away, and showing in dot-and-dash lines the position of the slide member projected in one direction.

Fig. 2 is a longitudinal sectional view, taken along the line 2—2 of Fig. 1.

Fig. 3 is a vertical sectional view, taken along the line 3—3 of Fig. 1.

Fig. 4 is a front elevation of the slide member of the device in detached flat relation.

Fig. 5 is an inside elevation of the holder or envelope member of the device in unfolded flat relation.

Fig. 6 is a front elevation, partially broken away, of a modified form of the invention.

Fig. 7 is a vertical sectional view, taken along the line 7—7 of Fig. 6.

Similar reference characters indicate corresponding parts throughout the several figures of the drawing.

Referring to the drawing, and more particularly to Figs. 1 to 5 thereof, the slide holder according to the exemplary embodiment of the invention illustrated therein comprises a rectangular holder or envelope member, open at each end, and consisting of a rectangular front portion 10, a rectangular back portion 11, adapted to be folded downwardly upon the front portion along a longitudinal fold line 12, and a longitudinally extending flap portion 13, adapted to be folded upwardly from the lower edge of the front portion 10 along a longitudinal fold line 14 into the space between the front and back portions.

The flap 13 constitutes a securing flap for the holder or envelope member and also an element of the limit stop means for cooperation with the slide member, being provided for this purpose with a longitudinal slot 15, preferably midway between its longitudinal edges and having its ends spaced a predetermined distance from the ends of the flap. The flap 13 is adapted to be adhesively secured by glue or the like to the inner surface of the lower edge portion of the back portion 11, along the portion of the flap 13 between the slot 15 and the fold line 14 and also along the end portions of the flap between the ends of the slot 15 and the end edges of the flap, this glued area being shown in Fig. 5 by the glue 16 applied to the inner surface of the edge portion of the back 11 preparatory to having the flap 13 engaged and secured thereto.

The front portion 10 is provided with longitudinal transversely spaced parallel sight openings 17 and 18 through which slide member containing data to be read in cooperation with data upon the face of the holder is visible. At the ends of the front and back portions 10 and 11 there are provided thumb notches 19 to facilitate the pulling out of the slide member by grasping its ends between the fingers. Calendar data 20 and 21 is printed upon the outer face of the front member 10 in relation to the sight openings 17 and 18.

The slide member 22 is of rectangular form to fit slidably within the holder or envelope member, and centrally of its lower marginal portion is provided with an upwardly projecting lanced out stop tab 25 integrally connected along the bending line 24. The space between the lower edge of the slide member and the bending line

24 is slightly less than the width of the portion of the flap 13 between the slot 15 and the fold line 14, so that in the assembled relation as shown clearly by the sectional view, Fig. 3, the bending line 24 is disposed in the space between the flap 13 and the front portion 10 below the slot 15, and the stop tab portion 25 is engaged through the slot 15 and projects above it between the portion of the flap 13 above the slot 15 and the back portion 11, so that as the slide is pulled outwardly in either direction the stop tab 25 has free sliding movement until it engages the opposed end of the slot 15. The length of the slot as well as the width of the stop tab may be determined so as to limit the projection of the slide member to any desired extent in either direction of movement.

Upon the forward side of the slide member there is printed calendar data 26 and 27 in position to show through the slide openings 17 and 18 and adapted through sliding movement of the slide member for cooperation with the calendar data 20 and 21 upon the face of the holder or envelope member.

In Figs. 6 and 7 I have illustrated a modified form of the invention in which the front portion 10 of the holder or envelope member is provided at its lower edge with a securing flap 13a folded upwardly and secured by gluing to the lower marginal edge portion of the back portion 11, this flap being provided centrally of its upper edge with a projecting stop tab portion 25a engaged through a slot 15a provided longitudinally of the slide member adjacent to and slightly above the upper edge of the flap portion 13a. The ends of the slot terminate in spaced relation to the ends of the slide member, and as the slide member is projected in either projection from the holder or envelope member it is limited in its projecting movement by engagement of the ends of the slot with the stop tab portion 25a. As in the first embodiment the length of the slot, as well as the width of the tab portion may be determined to limit the projection of the slide member to any desired extent in either direction.

I have illustrated and described preferred and satisfactory embodiments of the invention, but it will be understood that changes may be made therein, within the spirit and scope thereof, as defined in the appended claims.

Having thus described my invention what I claim and desire to secure by Letters Patent is:

1. In a slide holder device, a holder element comprising front and back parts and a securing flap portion integral with one of said front and back parts and secured to the inner side of the other part whereby said flap portion is enclosed between said front and back parts, a slide element engaged within said holder element for longitudinal sliding movement including a marginal portion overlying said securing flap portion, and limit stop means cooperating between said securing flap portion and said overlying marginal portion comprising a longitudinal slot in one of said portions having its ends spaced a predetermined distance from the ends of said

portion and a transversely projecting stop tab integral with said other portion and engaged through said slot, both said slot and tab being enclosed within and concealed by said front and back parts.

2. In a slide holder device, a holder element comprising front and back parts and a securing flap portion integral with said front part extending inwardly from a longitudinal edge of 10 said front part between said front and back parts and provided with a longitudinal slot intermediate its longitudinal edges having its ends spaced a predetermined distance from the ends of said flap portion, said flap portion being secured to the inner side of said back portion at one side of said slot and being unsecured at the other side of said slot, a slide element engaged within said holder element for longitudinal sliding movement, and a stop tab carried by said 20 slide element engaged through said slot for longitudinal sliding movement therein, abutment of said tab with the ends of said slot limiting the sliding movement of said slide element, both said slot and tab being enclosed within and concealed by said front and back parts.

3. In a slide holder device, a holder element comprising front and back parts and a securing flap portion integral with said front part extending inwardly from a longitudinal edge of 30 said front part between said front and back parts and provided with a longitudinal slot intermediate its longitudinal edges having its ends spaced a predetermined distance from the ends of said flap portion, said flap portion being secured to the inner side of said back part at one side of said slot and being unsecured at the other side of said slot, a slide element engaged within said holder element for longitudinal sliding movement, and a stop tab integral with said 40 slide element spaced from a longitudinal edge thereof engaged through said slot and disposed at the rearward side of said unsecured part of said flap portion at one side of said slot for longitudinal sliding movement in said slot, engagement of said stop tab with the ends of said slot limiting sliding movement of said slide element, both said slot and tab being enclosed within and concealed by said front and back parts.

4. In a slide holder device, a holder element 50 comprising front and back parts and a securing flap portion integral with said front part extending upwardly from its lower edge between said front and back parts and secured to the inner side of said back part, a stop tab portion integral 55 with the upper edge of said flap portion projecting upwardly therefrom in unsecured relation to said back part, and a slide element engaged within said holder element for longitudinal sliding movement having a longitudinal slot spaced from its lower edge and engaged by said stop tab, whereby longitudinal sliding movement of said slide element is limited by the engagement of the ends of said slot with said stop tab, both said slot and tab being enclosed within and concealed by said front and back parts.

MAX VOGEL.
